UNITED STATES PATENT OFFICE.

EDWARD ERICKSON, OF CLIFTONDALE, MASSACHUSETTS, ASSIGNOR TO VICTOR SHOE MACHINERY COMPANY, OF LYNN, MASSACHUSETTS, A CORPORATION OF MASSACHUSETTS.

PRESSER-FOOT MECHANISM FOR SEWING-MACHINES.

1,244,041.

Specification of Letters Patent. Patented Oct. 23, 1917.

Application filed July 3, 1916. Serial No. 107,868.

To all whom it may concern:

Be it known that I, EDWARD ERICKSON, a subject of the King of Sweden, and a resident of Cliftondale, in the county of Essex and Commonwealth of Massachusetts, have invented certain new and useful Improvements in Presser-Foot Mechanisms for Sewing-Machines, of which the following is a specification.

10 This invention relates to presser foot mechanisms for sewing machines and has for its object the production of a mechanism of this character in which the presser foot when being raised from the work support 15 will move through the same arc as the needle moves when pulling the loop through the work.

Another object of the invention is the production of means actuated directly from 20 the presser foot lever for measuring off the required amount of thread for varying thicknesses of material.

A further object of the invention is the production of a presser foot mechanism 25 which will run smoothly and which may be used successfully on a rapid stitcher.

The invention consists in certain novel features of construction and arrangement of parts which may be fully understood by 30 reference to the description of the drawings and to the claims hereinafter given.

For the purpose of illustrating the invention, one preferred form thereof is illustrated in the drawings, this form having 35 been found to give satisfactory and reliable results, although it is to be understood that the various instrumentalities of which the invention consists can be variously arranged and organized and that the invention 40 is not limited to the precise arrangement and organization of these instrumentalities as herein shown and described.

Of the drawings:

Figure 1 represents a vertical section of a 45 portion of a sewing machine and showing a presser foot mechanism embodying the principles of the present invention, said section being on line 1—1 on Fig. 3.

Fig. 2 represents a vertical section of the 50 same looking from the opposite direction.

Fig. 3 represents a horizontal section on line 3, 3 on Fig. 2.

Fig. 4 represents a sectional detail showing the thread measuring devices.

Fig. 5 represents a section on line 5 on 55 Fig. 3.

Fig. 6 represents a section on line 6 on Fig. 3, and

Fig. 7 represents a detail of a portion of the presser foot actuating device with a 60 part thereof cut in section on line 7 on Fig. 1.

Similar characters designate like parts throughout the several figures of the drawings.

In the drawings, 10 represents a portion of a frame of a sewing machine having mounted therein a revoluble shaft 11, said shaft having mounted thereon and secured thereto the cam members 12 and 13 and the eccentric actuating member 14. Between the cam disks 12 and 13 is positioned a collar 15 splined to the shaft 11, and surrounding said collar 15 and freely movable thereon is the hub 16 of an oscillating lever 17 having a rearwardly extending arm 18 to which is pivoted at 19 a rod 20, the opposite end of which is adapted to be secured to a treadle or some other similar operating device.

To the rod 20 is secured at 21 a spring 22, the opposite end of which is secured to a stud 23 on a fixed part of the frame 10. This spring 22 normally retains the lever 17—18 in the position indicated in Fig. 1 of the drawings. When it is desired to move the lever 17 about the axis of the shaft 11, the rod 21 will be moved upwardly by means of any suitable treadle mechanism against the tension of the spring 22.

The machine is provided with the usual work support 24 and has mounted in a bracket 25 a laterally extending pin 26 on which is mounted the awl carrier 27 having an arm 28 extending toward the rear of the machine to which is pivotally connected the rod 29, the opposite end of which is connected to any suitable actuating mechanism adapted to oscillate the awl carrier 27 about the axis of the pin 26 during each stitch forming operation.

The carrier 27 is provided with the usual curved awl 30. There is also mounted upon the pin 26 a needle carrier 31 having secured thereto the usual curved barbed needle 32. The awl carrier is provided with some means such as the member 33 for moving the awl carrier laterally when it is de-

65

sired to feed the work. Coacting with the work support 24 is a presser foot 34 clamped within the outer end of a lever 35, the opposite end of which is pivotally connected at 36 with an arm 37 having a hub 38 surrounding a collar 39 splined to the shaft 11. The shaft 11 with the collar 39 splined thereto is adapted to freely revolve within the hub 38.

10 It is obvious that the arm 37 on the hub 38 is adapted to move in various radial positions about the axis of the shaft 11 and control the movement of the presser foot lever when it is actuated by the devices provided 15 therefor. Intermediate the ends of the lever 35 is a hub 39 through which extends a pivot member 40 extending laterally from one face of a disk 41 from the opposite face of which extends a cylindrical support 42, the 20 axis of which is out of alinement with the axis of the pivot member 40. This support 42 has mounted thereon a sleeve 43 having an enlarged head 44 at its outer end. The head 44 is provided with a peripheral groove 25 45 in which are positioned the segments 46 and 47. The segment 46 is prevented from moving by means of a pin 48 extending through an elongated curved slot 50 in the 30 and being threaded to the frame 10, as indicated at 51 in Fig. 7 of the drawings.

The segment 47 has a slight movement about the axis of the cylindrical support 42 and is provided with a projection 52 at one end, while between its opposite end and the 35 opposed end of the segment 46 is a helical spring 53 adapted to move the segment in the direction of the arrow *a* in Fig. 6 of the drawings. The head 44 has a cylindrical opening 54 extending therethrough, into 40 which the periphery of the cylindrical support 42 extends, as indicated in Fig. 5 of the drawings. In this cylindrical opening 54 is positioned a flat-sided semi-cylindrical member 55, between the flat side of which and 45 the periphery of the cylindrical support 42 is located a locking roller 56. From the opening 54 to the periphery of the head 44 is a narrow slit 57 which provides a means whereby when the walls of said slit are 50 moved toward each other the semi-cylindrical member 55 will be clamped in its adjusted position, within the opening 54. To permit the member 55 to be adjusted in the opening 54, said member is provided with 55 the slot 58 in its outer end, as indicated in dotted lines in Fig. 1 of the drawings.

Surrounding the head 44 is a split annular member 59 having an arm 60 extending therefrom and being provided with two 60 separate ears 61—62 on opposite sides of said split. Extending through the ear 62 and threaded to the ear 61 is a clamping member 63, by adjusting which the annular member 59 may be securely clamped to the 65 head 44 and cause it to be moved therewith,

and at the same time the walls of the slit 57 in the head 44 will be forced toward each other and clamp the member 55 in its adjusted position.

The rear end of the arm 60 is provided 70 with a roll 64 on one side thereof, said roll being positioned in a cam path 65 in the cam disk 13. On the opposite side of said arm 60 is another roll 66 which is positioned in a cam path 67 formed in the side face of 75 the lever 17. The cam disk 13 revolves in the direction of the arrow *b* on Fig. 1 of the drawings, and is provided with a cam throw 68, as indicated in said figure. In each revolution of the disk 13 the throw 68 80 acting upon the roller 64 will cause an oscillation of the cylindrical support 42 and raise the presser foot 34 from the work support 24.

Owing to the fact that the movement of 85 the lever 35 is controlled by means of the pivotal connection 36 with the arm 37 extending from the hub 38 surrounding the revoluble shaft 11, when the support 42 is oscillated, and the pivot 40 eccentrically 90 mounted thereon is moved about the axis of said support 42, the presser foot 34 will be moved in the same arc that the needle 32 moves when it is moving upwardly and pulling the loop through the work. 95

The cam path 65 is provided with a widened portion 69 as indicated in Fig. 1 of the drawings. Owing to the fact that the roll 66 is positioned in the cam path 67 of the lever 17, and the roll 64 is in the cam path 65, it is obvious that no oscillating movement of the lever 17 can be effected until the widened portion 69 of the cam path 65 is opposite the roll 64. 100

When the widened portion 69 has reached 105 a point opposite the roll 64 the rod 20 may then be forced upwardly and the cam path 67 acts upon the roll 66 to force the arm 60 downwardly and toward the front of the machine. This movement will cause the 110 roller 56 to strike against the finger 70 extending upwardly from the segment 46 and thus unlock the member 55 from the cylindrical support 42. The projection 71 on the lever 17 will then contact with the projection 72 formed upon a plate 73 secured to the end of the cylindrical support 42 by means of the nut 74. When the projection 71 has engaged with the projection 72 the support 42 will be moved about its axis and 115 cause the lifting of the presser foot independently of the cam throw 68. A spring 75 having one end surrounding the pin 48 and the other end extending beneath the lateral extension 76 on the plate 73, normally retains the presser foot 34 in contact with the upper surface of the work. 120

Below the revoluble shaft 11 is a member 77 pivoted to the frame 10 at 78 and having a slot 79 therein through which extends a 125 130

clamping bolt 80 by means of which the member 77 may be locked in adjusted position when moved through a limited arc about the pivot 78. The upper end of the member 77 is provided with a stop projection 81 extending laterally from the upper end of said member, as indicated in Fig. 4 of the drawings.

At the outer end of the stop member 81 is a plate 82 having secured thereto the revolvable sheaves 83 and 84. Pivotally mounted upon the plate 82 is a pawl 85, the free end of which is adapted to engage with the rear flat face of the stop projection 81, said pawl being normally forced against said projection by means of the spring 86.

This pawl 85 permits the thread *t* to be moved from the sheave 84 to the work, but prevents said thread from being moved in the opposite direction.

Coacting with the front face of the stop member 81 is a finger 87 projecting from the lower end of an arm 88 pivoted at 89 to the lever 35. This arm 88 has revolvably mounted therein a roll 90 adapted to be engaged by the eccentric actuating member 14 during each rotation of the shaft 11. About a stud 91 fixed to the frame 10 is a helical spring 92 the upper end 93 of which engages the arm 88 and normally retains the finger 87 in contact with the thread *t* passing over the stop projection 81.

From a stripper of any well-known form of wax pot, the thread *t* passes between the front face of the stop projection 81 and the finger 87, then over the sheave 83 and around the finger 87 to the sheave 84, from which it passes between the rear face of the projection 81 and the pawl 85, all as shown in Fig. 2 of the drawings.

It is obvious, inasmuch as the thread *t* is prevented by means of the pawl 85 from moving in a direction away from the work being operated upon, that during every movement of the arm 88 about its pivot 89 a quantity of thread will be drawn from the source of supply preparatory to its being used in the formation of the next stitch. The amount of thread thus measured off depends entirely upon the position of the roll 90 relatively to the path of movement of the eccentric actuating member 14. It is self-evident that the nearer the roll 90 is to the axis of the shaft 11, the greater will be the amount of thread measured off during every revolution of the actuating member 14.

As the thickness of the material being operated upon varies, the position of the presser foot will be automatically varied, and the location of the roll 90 relatively to the actuating member 14 will be changed, thereby determining the length of thread necessary for the various thicknesses of stock.

A spring 94 interposed between a pin 95

in the frame 10 and a pin 96 in the lever 60 normally retains the roller 64 in contact with the inner wall of the cam path 65. When it is desired to place new work upon the work support, the operator raises the rod 20 and thereby moves the lever 17 so that its projection 71 will contact with the projection 72 and cause the presser foot lever support 42 to be moved about its axis and the presser foot 34 raised sufficiently for the admission of the work.

It is obvious that the widened portion 69 of the cam path 65 must be opposite the roll 64 at this time, the cam disk 13 either having been rotated about the axis of the shaft 11 by hand or having been stopped at this point by means of a stop motion generally used in machines of this type.

The cam path 67 acting on the roller 66 during the oscillation of the lever 17 will unlock the support 42 so that it may be freely turned about its axis when the arm 72 is depressed by the projection 71.

While the work is being operated upon the support 42 will be unlocked during each revolution of the cam disk 13 whenever the throw 68 passes the roll 64. When the roll 64 passes down the inclined portion 97 of the cam path 65, it will cause the support 42 to be locked, and will then force the presser foot 34 downwardly a predetermined distance to give a required and uniform pressure.

The presser foot 34 is provided with a cylindrical shank 100 which is positioned in an opening 101 extending horizontally through the forward end of the lever 35, said lever being provided with a peripheral slot 102 extending to said opening 101, as indicated in Fig. 2.

A clamping member 103 with its shank extending across said slot and threaded at 104 to said lever 35 is adapted to clamp the presser foot 34 in adjusted position.

The presser foot 34 is provided with a heel 106 the position of which relatively to the needle 32 may be varied as desired by loosening the member 103, moving the presser foot 34 about the axis of the shank 100 and then again turning the member 103 to lock the presser foot in its new position.

When the length of the stitches is varied, it is very desirable that the position of the presser foot should be varied so that the end 107 thereof will be as close as possible to the outer position of the awl 30. This adjustment may be made by loosening the member 103, moving the shank 100 endwise in the opening 101, and then again tightening the member 103.

This means of adjusting the presser foot relatively to its supporting lever and in directions substantially perpendicular to each other is of great advantage.

Owing to the location of the pivot 40 at

quite a distance from the under face of the presser foot, this under face maintains a position substantially parallel with the upper face of the work support even when said 5 presser foot is raised.

By causing the presser foot 34 to move in the same arc that the needle moves, the heel 106 of the presser foot 34 is always maintained in the same relation with the 10 needle 32 regardless of the thickness of the work being operated upon. This is of great advantage, for heretofore the presser foot would become more and more separated from the needle as the thickness of the material increased, and imperfect results would consequently be obtained.

On the sleeve 59 is a projection 108 with which the arm 72 contacts to prevent the presser foot 34 from coming into contact 20 with the work support 24. Normally the under face of the presser foot 34 is separated from the upper face of the work support 24 a distance at least equal to the movement that would be imparted thereto by the 25 cam throw 97 to give the necessary pressure to the material being operated on.

By retaining the presser foot 34 normally separated from the work support 24 the accidental breaking or bending of the parts 30 when pressure is applied is entirely obviated.

It is believed that the operation and many advantages of this invention will be fully understood from the foregoing description.

Having thus described my invention, I 35 claim:

1. In a device of the class described, a work support; an oscillating curved needle; a presser foot; a lever therefor; a link pivotally connected at one end to the rear end 40 of said lever; a pivot member for the opposite end of said link; a pivot for said lever intermediate its ends; an oscillating member on which said pivot is eccentrically mounted; and means for transmitting movement to said oscillating member.

2. In a device of the class described, a work support; an oscillating curved needle; a presser foot; a lever therefor; a link pivotally connected at one end to the rear end 50 of said lever; a pivot member for the opposite end of said link; a pivot for said lever intermediate its ends; an oscillating member on which said pivot is eccentrically mounted; and means for transmitting movement to said oscillating member and locking it from movement at predetermined times.

3. In a device of the class described, a work support; an oscillating curved needle; a presser foot; a lever therefor; a link pivotally connected at one end to the rear end 60 of said lever; a pivot member for the opposite end of said link; a pivot for said lever intermediate its ends; an oscillating member on which said pivot is eccentrically mount-

ed; and cam-controlled means for transmitting movement to said oscillating member.

4. In a device of the class described, a work support; an oscillating curved needle; a presser foot; a lever therefor; a link pivotally connected at one end to the rear end 70 of said lever; a pivot member for the opposite end of said link; a pivot for said lever intermediate its ends; an oscillating member on which said pivot is eccentrically mounted; a sleeve surrounding said oscillating member and provided with a longitudinal opening at its outer end extending to the periphery of said oscillating member; a roller in said opening; and a cam controlled 75 member coacting with said roller to cause it to impinge upon said oscillating member.

5. In a device of the class described, a work support; an oscillating curved needle; a presser foot; a lever therefor; a link pivotally connected at one end to the rear end 80 of said lever; a pivot member for the opposite end of said link; a pivot for said lever intermediate its ends; an oscillating member on which said pivot is eccentrically mounted; a sleeve surrounding said oscillating member and provided with a longitudinal opening at its outer end extending to the periphery of said oscillating member; a roller in said opening; and a cam controlled 85 member coacting with said roller to cause it to impinge upon said oscillating member; and means for moving said roller into an unlocked position at predetermined times.

6. In a device of the class described, a presser foot; a lever therefor; means for controlling the movement of said presser foot lever; a pivot for said lever eccentrically mounted upon a cylindrical support; a sleeve surrounding said support; a cam controlled lever secured to said sleeve; and means carried by said sleeve for locking it to said support at predetermined times.

7. In a device of the class described, a presser foot; a lever therefor; means for controlling the movement of said presser foot lever; a pivot for said lever eccentrically mounted upon a cylindrical support; a sleeve surrounding said support; a cam controlled lever adjustably secured to said 110 sleeve; and means carried by said sleeve for locking it to said support at predetermined times.

8. In a device of the class described, a presser foot; a lever therefor; means for controlling the movement of said presser foot lever; a pivot for said lever eccentrically mounted upon a cylindrical support; a sleeve surrounding said support; a cam controlled lever secured to said sleeve; and means carried by and adjustable within said sleeve for locking it to said support at predetermined times.

9. In a device of the class described, a presser foot; a lever therefor; means for 130

- controlling the movement of said lever; a pivot for said lever eccentrically mounted upon a cylindrical support; a headed sleeve surrounding said support and having a longitudinal opening in said head; a flat-sided member in said opening; a roller between the flat side of said member and said support; and a cam-controlled lever secured to said sleeve.
10. In a device of the class described, a presser foot; a lever therefor; means for controlling the movement of said lever; a pivot for said lever eccentrically mounted upon a cylindrical support; a headed sleeve surrounding said support and having a longitudinal opening in said head; a flat-sided member in said opening; a roller between the flat side of said member and said support; a cam controlled lever; and means 20 for clamping said lever to said sleeve.
11. In a device of the class described, a presser foot; a lever therefor; means for controlling the movement of said lever; a pivot for said lever eccentrically mounted upon a cylindrical support; a headed sleeve surrounding said support and having a longitudinal opening in said head; a flat-sided member adjustably mounted in said opening; a roller between the flat side of said member and said support; a cam-controlled lever secured to said sleeve; and means 30 for clamping said flat-sided member in adjusted position.
12. In a device of the class described, a presser foot; a lever therefor; means for controlling the movement of said lever; a pivot for said lever eccentrically mounted upon a cylindrical support; a headed sleeve surrounding said support and having a longitudinal opening in said head; a flat-sided member adjustably mounted in said opening; a roller between the flat side of said member and said support; a cam-controlled lever; and means for simultaneously 40 clamping said lever to said sleeve and said flat sided member in its adjusted position within said sleeve.
13. In a device of the class described, a presser foot; a lever therefor; means for controlling the movement of said lever; a pivot for said lever eccentrically mounted upon a cylindrical support; a headed sleeve surrounding said support and having a longitudinal opening and a peripheral groove in said head; a flat-sided member in said opening; a roller between the flat side of said member and said support; a cam-controlled lever secured to said sleeve; two disk segments in said peripheral groove provided with fingers extending toward each other on opposite sides of said roller; and a spring interposed between the opposite ends of said segments.
14. In a device of the class described, a presser foot; a lever therefor; means for controlling the movement of said lever; a pivot for said lever eccentrically mounted upon a cylindrical support; a headed sleeve surrounding said support and having a longitudinal opening and a peripheral groove in said head; a flat sided member in said opening; a roller between the flat side of said member and said support; a cam-controlled lever secured to said sleeve; two disk segments in said peripheral groove provided with fingers extending toward each other on opposite sides of said roller; and a spring interposed between the opposite ends of said segments.
15. In a device of the class described, a presser foot; a lever therefor; means for controlling the movement of said lever; a pivot for said lever eccentrically mounted upon a cylindrical support; a headed sleeve surrounding said support and having a cylindrical opening and a curved slot extending longitudinally of said head; a stationary pin extending through said slot; a flat-sided member positioned in said opening; a roller in said opening between the flat side of said member and said support; and cam-controlled mechanism for moving said sleeve relatively to said support and said support and sleeve in unison.
16. In a device of the class described, a presser foot; a lever therefor; means for controlling the movement of said lever; a pivot for said lever eccentrically mounted upon a cylindrical support; a headed sleeve surrounding said support and having a cylindrical opening and a curved slot extending longitudinally of said head, said head having a slit extending from its periphery to said opening; means for forcing the walls of said slit toward each other to grip said flat-sided member; a stationary pin extending through said slot; a flat-sided member positioned in said opening; a roller in said opening between the flat side of said member and said support; and cam controlled mechanism for moving said sleeve relatively to said support and said support and sleeve in unison.
17. In a device of the class described, a presser foot; a lever therefor; means for controlling the movement of said lever; a pivot for said lever eccentrically mounted upon a cylindrical support; a headed sleeve surrounding said support and having a cylindrical opening and a curved slot extending longitudinally of said head; a stationary pin extending through said slot; a flat-sided member positioned in said opening; a roller in said opening between the flat side of said member and said support; cam controlled mechanism for moving said sleeve relatively to said support and said support and sleeve.

in unison; and means for limiting the movement of said roller in either direction.

18. In a device of the class described, a presser foot; a lever therefor; means for controlling the movement of said lever; a

5 pivot for said lever eccentrically mounted upon a cylindrical support; a headed sleeve surrounding said support and having a cylindrical opening and a curved slot extending longitudinally of said head; a stationary pin extending through said slot; a flat-sided member positioned in said opening; a roller in said opening between the flat side of said member and said support; cam controlled

10 mechanism for moving said sleeve relatively to said support and said support and sleeve in unison; and means for oscillating said support independently of said sleeve actuating devices.

15 19. In a device of the class described, a presser foot; a lever therefor; means for controlling the movement of said lever; a pivot for said lever eccentrically mounted upon a cylindrical support; a cam-controlled

20 mechanism for automatically oscillating said support to raise the presser foot prior to the feeding of the work; and independent means for raising the presser foot manually.

25 20. In a device of the class described, a presser foot; a lever therefor; means for controlling the movement of said lever; a pivot for said lever eccentrically mounted upon a cylindrical support; cam-controlled

30 mechanism for automatically oscillating said support to raise the presser foot prior to the feeding of the work; a spring pressed arm secured to the end of said support; an oscillating actuator adapted to engage said arm and move said support about its axis to

35 raise said presser foot.

40 21. In a device of the class described, a presser foot; a lever therefor; means for controlling the movement of said lever; a pivot for said lever eccentrically mounted

45 upon a cylindrical support; a revolute shaft; a cam secured thereto having a cam path provided with a throw and a widened portion; mechanism for actuating said support including a radial lever; a roll on

50 each side of said lever, one of which is positioned in said cam path; an arm secured to

the end of said support; a member freely movable about said shaft and provided with a cam groove in which the other roll is positioned, the outer wall of said cam groove coinciding with the outer wall of the widened portion of the path in said revolute cam; and a projection on said movable

55 member adapted to engage said arm to raise the presser foot.

60 22. In a device of the class described, a presser foot; a lever therefor; means for controlling the movement of said lever; a pivot for said lever eccentrically mounted

65 upon a cylindrical support; a revolute

shaft; a cam secured thereto having a cam path provided with a throw and a widened portion; mechanism for actuating said support including a radial lever; a roll on said lever and positioned in said cam path; 70 an arm secured to said support; a member freely revoluble about said shaft and having a projection adapted in its movement to engage said arm to raise the presser foot; and means preventing the movement of said member about said shaft until the roll on said lever is in the widened portion of said cam path.

75 23. In a device of the class described, a presser foot; a lever therefor; means for controlling the movement of said lever; a pivot for said lever eccentrically mounted upon a cylindrical support; a revoluble

80 shaft; a cam secured thereto having a cam path provided with a throw and a widened portion; mechanism for actuating said support including a radial lever; a roller on said lever and positioned in said cam path; an arm secured to said support; a member freely revoluble about said shaft and having a projection adapted in its movement to engage said arm to raise the presser foot; and means preventing the movement of said member about said shaft until the roll on said lever reaches a predeterminind point in 95 said cam path.

90 24. In a device of the class described, a pivoted lever; a presser foot carried thereby; a revoluble shaft; an eccentric mounted thereon and revoluble therewith; an arm 100 pivotally mounted on said lever; a roller carried thereby normally held in the path of said eccentric; means for controlling the movement of said presser foot lever; means for actuating said lever at predetermined 105 times; and a thread measuring device actuated by the movements of said arm about its pivot.

110 25. In a device of the class described, a pivoted lever; a presser foot carried thereby; a thread measuring device including in part an arm pivoted to the presser foot lever; a revoluble shaft; and means on said shaft for actuating said arm at predeter- 115

120 mined times. 26. In a device of the class described, a pivoted lever; a presser foot carried thereby; a thread measuring device including in part an arm pivoted to the presser foot lever; a revoluble shaft; means on said shaft 125 for actuating said arm at predetermined times; and means for varying the movement of said arm for various thicknesses of material.

130 27. In a device of the class described, a pivoted lever; a presser foot carried thereby; a thread measuring device including in part an arm pivoted to the presser foot lever; a revoluble shaft; means on said shaft for actuating said arm at predetermined

times; and means permitting the movement of the thread being measured only in the direction from the source of supply.

28. In a device of the class described, a pivoted lever; a presser foot carried thereby; a thread measuring device including in part an arm pivoted to the presser foot lever; a revolute shaft; means on said shaft for actuating said arm at predetermined times; and a spring pressed pivoted member adapted to engage the thread being measured and prevent its movement toward the source of supply.

29. In a device of the class described, a pivoted lever; a presser foot carried thereby; means for varying the position of said lever for various thicknesses of material; a member provided with a stop projection; a thread sheave on each side of said projection; an arm pivoted to said presser foot lever and provided with a thread engaging finger; means for normally retaining said finger in contact with the thread on the face of said projection; and means for actuating said arm during each stitch forming operation.

30. In a device of the class described, a pivoted lever; a presser foot carried thereby; means for varying the position of said lever for various thicknesses of material; an adjustable member provided with a stop projection; a thread sheave on each side of said projection; an arm pivoted to said presser foot lever and provided with a thread engaging finger; means for normally retaining said finger in contact with the thread on the face of said projection; and means for actuating said arm during each stitch forming operation.

31. In a device of the class described, a pivoted lever; a presser foot carried thereby; means for varying the position of said lever for various thicknesses of material; a member provided with a stop projection; a

thread sheave on each side of said projection; an arm pivoted to said presser foot lever and provided with a thread engaging finger; means for normally retaining said finger in contact with the thread on the face of said projection; means for actuating said arm during each stitch forming operation; and means mounted upon said stop projection member for restraining the thread to movement in one direction only.

32. In a device of the class described, a pivoted lever; a presser foot carried thereby; means for varying the position of said lever for various thicknesses of material; a member provided with a stop projection; a thread sheave on each side of said projection; an arm pivoted to said presser foot lever and provided with a thread engaging finger; means for normally retaining said finger in contact with the thread on the face of said projection; means for actuating said arm during each stitch forming operation; and a pivoted pawl coacting with said stop projection for restraining the thread to movement in one direction only.

33. In a device of the class described, a pivoted lever; a presser foot carried thereby; means for varying the position of said lever for various thicknesses of material; a member provided with a stop projection; a thread sheave on each side of said projection; an arm pivoted to said presser foot lever and provided with a thread engaging finger; means for normally retaining said finger in contact with the thread on the face of said projection; and a revolute member for actuating said arm during each stitch forming operation.

Signed by me at 4 Post Office Sq., Boston, Mass., this 16th day of June, 1916.

EDWARD ERICKSON.
